E. C. LARRY

RAILWAY SIGNALING SYSTEM

Filed Dec. 14, 1925

UNITED STATES PATENT OFFICE.

EDWIN C. LARRY, OF ROCHESTER, NEW YORK, ASSIGNOR TO GENERAL RAILWAY SIGNAL COMPANY, OF ROCHESTER, NEW YORK.

RAILWAY SIGNALING SYSTEM.

Application filed December 14, 1925. Serial No. 75,337.

This invention relates to automatic block signaling systems, and more particularly to means for checking the failure of a block signal to give a danger or stop indication when the block at the entrance of which it is located, is occupied.

In one type of block signal system, to which the present invention more particularly relates, polarized track or line circuits are used to govern the indications of semaphore signals, the polarity of said track or line circuits being reversed by pole-changers mechanically operated by the signals. If, for any reason, a semaphore signal should stick in its clear position and fail to assume its stop position when it should, the pole-changer operated by that signal fails to reverse the polarity of the circuit for the signal next in the rear, with the result that the signal in the rear indicates clear when it should indicate caution.

In accordance with the present invention, it is proposed to cause the next signal in the rear of a signal in question to remain in the stop position if the signal in question is out of order and is giving a false proceed indication, that is, if it fails to go to stop when it should. More specifically it is proposed to provide a stick relay at each signal location in connection with a circuit arrangement whereby the next signal in the rear of such signal location will indicate stop, or danger, when the stick relay at the signal location mentioned is de-energized, and to provide means for energizing such stick relay which is closed only after the signal adjacent thereto assumes the stop position. In other words, the stick relay mentioned is de-energized each time a train passes and if the signal does not assume the danger position in response to such passage of the train, the stick relay will not be again picked up and the signal next in the rear is caused to indicate danger.

Other objects, purposes, and characteristic features of the invention will readily appear as the description thereof progresses.

In describing the invention in detail, reference will be made to the single drawing which shows one track of a double track railroad in which the normal direction of traffic is from left to right, as indicated by the arrow, and in which the track rails 1 are divided into blocks by insulating joints

2, of which the block I and the adjacent ends of two other blocks H and J only, have been shown. Since the various circuits and devices at each signal location are the same, like parts of each block are designated by like reference characters having distinctive exponents. The block I has bridged across the entrance end thereof an alternating current track relay T, and the exit end of this block is provided with the usual trackway source of energy, which in the particular embodiment of the invention illustrated comprises a transformer 4¹. Since the present invention is more particularly applicable to semaphore signals, there has been provided at the entrance to each block, a semaphore signal Z which normally assumes its clear indicating position by reason of energization of the clear wire 5, such signal assuming the caution position if the caution wire 6 only is energized, and assumes the danger position if neither of these two wires are energized; these signals including the usual electrically operated mechanism, which for convenience has been omitted from the drawings, the power for operating the signals being derived from a suitable local source of energy such as a battery having its terminal B connected to the contact 7 of the track relay and having its other terminal connected to a common return wire C. These semaphore signals Z also have a contact blade 8 associated therewith, which assumes a position corresponding to that of the signal blade, and are further provided with snap pole changer contacts 9 and 10, which change quickly from their normal to their abnormal dotted position as the semaphore signal blade moves from either the clear or caution to the danger position.

Each of the blocks is provided with a stick relay SR, which is normally energized through two partial circuits which, for the relay SR¹, may be traced as follows:—(1) beginning at the terminal B of a suitable source of energy, contact 12¹ of the track relay T¹ wires 13¹ and 14¹, stick contact 15¹ of the relay SR¹, wires 16¹ and 17¹, winding of the relay SR¹ to the common return wire C connected to the other side of said source of energy, and (2) beginning at the terminal B of a suitable source of energy, contact 18, wires 19, 20, and 14¹, stick contact 15¹, wires 16¹, and 17¹, winding of the relay SR¹ to the

common return wire C connected to the other side of said source of energy. It should be noted that the track transformer 4¹ supplies track circuit current to the block I through 5 contacts 22¹ and 23¹ of the relay SR¹, so that the block I is deprived of track circuit current if the stick relay SR¹ is de-energized; also, it should be noted that the polarity of the track circuit current of the block I is reversed whenever the signal at the entrance to the block J is at danger by reason of the pole changer contacts 9¹ and 10¹ operated by the signal Z¹, and that such reversal of the track circuit current of block I causes the 10 track relay T to assume the reverse position and causes the signal Z to assume the caution position.

Operation.

20 In order to understand the embodiment of the invention illustrated clearly, it is considered expedient to first consider the movement of a train in the normal direction of traffic, when the signals are in working order, and to then assume the passage of a train when the signal Z¹ fails to go to danger upon the passage of the train by the signal. Let us assume that a train is moving from left to right in the block H 25 and that it enters the block I. The entrance of the train upon the track circuit of block I causes the track relay T to assume its deenergized position by reason of shunting action of the wheels of the train, thus causing the signal Z to assume its danger position because there is no current applied to either the clear wire 5 or the caution wire 6. Also, the dropping of track relay T causes the contact 18 to assume its pendent position, but this does not de-energize the stick relay SR¹, because this stick relay is held up through the contact 12¹. Also, movement of the contact 12 to its 30 pendent position causes the stick relay SR to assume its de-energized position, because the contact 18⁰ (not shown) of the track relay at the entrance to the block H is also in its pendent position and open, this on the assumption that the rear end of the 35 train is still in the block H. Immediately after the train has entered the block I, the signal Z assumes its danger position and causes a pickup circuit for the stick relay SR to be completed, which may be traced as follows: Beginning at the terminal B 40 of a suitable source of energy, semaphore contact 8, wires 25 and 17, winding of the stick relay SR to common return wire C connected to the other terminal of said 45 source of energy. This causes the stick relay SR to pick up and as soon as the rear end of the train leaves the block H, its stick circuit is again completed through the wire 20⁰. As the train passes the signal Z¹, the same signal, relay and circuit

changes take place at the signal Z¹ as just described in connection with the signal Z, so that no further discussion of the operation under proper working of the signals is deemed necessary.

Let us now assume that a train is moving from left to right through the block H and that it enters the block I, and causes the contact 18 to assume its pendent position for reasons heretofore given. Let us further assume that the train continues its movement and moves into the block J, that it causes de-energization of the stick relay SR¹. Let us further assume that the signal Z¹ is out of order and fails to assume the danger position. The failure of the semaphore of signal Z¹ to move to its danger position also causes failure of the pickup circuit for the stick relay SR¹ to be completed, so that, this stick relay SR¹ remains in its de-energized position, and permanently cuts off track circuit energy off of the block I, so as to cause the track relay T to remain de-energized thereafter. With the track relay 55 permanently de-energized, the signal Z will of course assume the danger position, and in so doing will cause the pole changer contacts 9 and 10 to assume the dotted position and in turn cause the signal at the entrance of the block H to assume the caution 60 position. In other words, since the signal Z¹ failed to go to danger, the signals at the entrance to the blocks I and H assume the danger and caution position, respectively, in spite of favorable traffic conditions 65 ahead.

In studying the circuit arrangements illustrating the present invention, it would at first appear that the contact 18 and the line wire 20 are entirely unnecessary. If, however, its contact 18 and line wire 20 were omitted, the sudden change of a signal by reason of the opening of a switch at a siding in a block, the backing of a train from a block in advance into the block in question, or the like, would cause signals to tumble down, so to speak, one after another, in the rear of such block; this being true because the sudden dropping of a track relay would cause its corresponding stick relay to drop, which in turn would cut off energy of the next block in the rear, thereby causing its track relay and stick relay to drop, etc., ad infinitum. With the provision of the contact 18 and line wire 20, however, the stick relay SR¹ will not drop even though the track relay T¹ drops due to the backing of a train into the block J, or the opening of a switch in the block J, or the like. In other words this undesirable "tumble down" is avoided by the provision of line wire 20 and contacts 18.

Having thus shown and described a single embodiment of the invention which not only causes a signal in the rear of a signal out

of order to go to danger; and the next signal in the rear thereof to go to caution, but which is so organized that no undesirable and unwarranted signal indications are given, due to the backing of a train into a block or the sudden change of a block from clear to danger for other reasons, such as the opening of a switch in such block; and having described the selected embodiment 10 rather specifically, it is desired to be understood that this has not been done to illustrate the exact construction preferably employed in practice, nor the scope of the invention, and that various changes and modifications 15 may be made to adapt the invention to the particular local conditions encountered in practicing the invention; for instance, a direct current source may be used instead of alternating current for track circuit purposes and polar neutral relays may be used instead of three-position relays, all without departing from the scope of the invention or the idea of means for carrying out the same.

25 What I claim as new is:—

1. In a block signaling system, the combination with a track divided into blocks by insulating joints, each block including a track relay and a source of energy connected to form the usual closed track circuit, a semaphore signal at the entrance to each block, and means effective if a particular semaphore signal does not assume the danger position upon the passage of a train 30 by such signal for causing the next semaphore signal in the rear to assume its danger position.

2. In a block signaling system the combination with a track divided into blocks by insulating joints each block including a track relay and a source of energy connected to form the usual closed track circuit, a semaphore signal at the entrance to each block, and means for causing the next semaphore signal in the rear of a particular semaphore signal to assume its stop position if that particular signal does not assume the danger position while the block at the entrance to which it is located is occupied.

3. In a block signaling system the combination with a track divided into blocks by insulating joints each block including a track relay and a source of energy connected to form the usual closed track circuit, a semaphore signal at the entrance to each block, a stick relay associated with each of said semaphore signals, means for de-energizing said stick relay upon the passage of a train by its associated semaphore signal, 55 and means for picking up said stick relay if such semaphore signal assumes its danger position upon the passage of a train thereby.

4. In a block signaling system, the combination with a track divided into blocks by insulating joints each block having the

usual track circuit including a track relay and a trackway source of energy, a signal at the entrance to each block, a stick relay associated with each signal and having a pickup circuit and a stick circuit, said pickup circuit including contacts operated by said signal and closed if it is in its stop position, said stick circuit including contacts closed if the track relay adjacent the associated signal is energized.

5. In a block signaling system, the combination with a track divided into blocks by insulating joints each block having the usual track circuit including a track relay and a trackway source of energy, a signal at the entrance to each block, a stick relay having a pick-up circuit and a stick circuit associated with each of said signals, said pick-up circuit including contacts closed only if the associated signal assumes the danger position, and said stick circuit comprising two partial circuits in multiple one of which includes contacts closed when the track relay adjacent the associated signal is energized and the other of which includes contacts closed when the next track relay in the rear is energized.

6. In a block signaling system, the combination with a track divided into blocks by insulating joints each block having the usual track circuit including a track relay and a trackway source of energy, a signal at the entrance to each block, a stick relay associated with each of said signals and having a pick-up circuit and a stick circuit, said pick-up circuit including contacts closed only if the associated signal assumes the danger condition, said stick circuit comprising two partial circuits in multiple one of which includes contacts closed when the track relay adjacent the associated signal is energized and the other of which includes contacts closed when the next track relay in the rear is energized, and means for causing said next signal in the rear to assume the danger condition when said stick relay is de-energized.

7. In a block signal system for railroads having blocks equipped with polarized track circuits, a semaphore signal for each block, a pole-changer operated by each signal, a source of current and electrical connections between each pole changer and the track rails of the block next in the rear for supplying track circuit current, and means associated with each track relay and its corresponding signal for breaking said electrical connections to cut off track circuit current from the block in the rear whenever said track relay is de-energized and said corresponding signal is not in its stop position.

8. A block signal system for railroads having polarized track circuits comprising in combination, a polarized track relay for each block, a semaphore signal for each block, a

1. pole-changer operated by each signal, a source of track circuit current, electrical connections between said source and pole-changer for reversing the polarity of the track circuit current for the block next in the rear, and means for interrupting the supply of current from said source to its track circuit in the rear whenever the track relays of a given block and the next block in the rear are de-energized and the signal at the entrance to said given block does not assume its stop position.
2. In a block signal system of the character described including polarized track circuits, the combination with a track relay for each block, of means responsive to the presence of a train in a given block and governed by the track relay of the block next in advance for cutting off the supply of track circuit current to the track circuit of said given block.
3. In a block signal system for railroads having tracks divided into blocks each provided with a track circuit, a semaphore signal at the entrance to each block, a pole-changer operated by each signal, means for governing each signal by the track circuit of its block and by the pole-changer operated by the signal next in advance, and automatic means for causing each signal to indicate stop independently of the occupancy of its block if the next block in advance is occupied and the signal of said next block in advance is not in its stop position.
4. In a block signal system having tracks divided into blocks each provided with a track circuit, a semaphore signal at the entrance to each block, a source of current and circuit connections including a pole-changer operated by each signal for governing the indications of the signal next in the rear, and means for breaking said circuit connections associated with a given signal if the block for that signal is occupied and that signal is not in its stop position. 45
5. In a block signal system having tracks divided into blocks each provided with a track circuit, a semaphore signal at the entrance to each block, a source of current and circuit connections including a pole-changer operated by each signal for governing the indications of the signal next in the rear, and means for automatically breaking said circuit connections associated with a given signal if its block and the next block in the rear are simultaneously occupied and for maintaining said break until said given signal assumes its stop position. 50
6. In testimony whereof I affix my signature.
EDWIN C. LARRY.
